UNITED STATES PATENT OFFICE

SHIRLEY S. FRENCH, OF CANTON, OHIO, ASSIGNOR TO THE BERGER MANUFACTURING COMPANY, A CORPORATION OF OHIO

LOCKER LATCH

Application filed May 26, 1928. Serial No. 280,846.

This invention has for its object the provision of a latching mechanism for a locker, which will be simple in operation, of sturdy construction, permit of easy assembly and 5 disassembly, and present withal a neat and attractive appearance.

Another object of the invention is to provide a door for a locker having a novel tubular formation at the edge thereof, which functions not only to reinforce the door, but at 10 the same time, serves as a bearing or supporting surface for slidably supporting a latching bar, and also serves to conceal the connection between the latching bar and the 15 door handle which is adapted to be directly connected thereto.

In the patent to Sturm and Caldwell, No. 1,671,328, there is described a latching mechanism for a locker in which a latching bar is enclosed 20 in a tubular housing or reinforcement at the edge of the door, the bar being positively forced into latching position by means of especially designed hooks or keepers which enter the housing and engage slots in the 25 latching bar. In assembling the aforesaid latching mechanism, it is necessary to insert the latching bar into one end of the housing and to push the bar up into the housing to a 30 position in which it may be engaged by the tenons of an especially designed handle.

In accordance with the present invention, the positioning or assembly of the latching bar is considerably facilitated by virtue of 35 the fact that the bar is placed on the exterior of the tubular reinforcement in a natural and simple manner, the bar being designed to be positively moved into latching position in the same manner as the latching bar described 40 in the aforesaid patent of Sturm and Caldwell.

These and other objects of the invention will become more readily apparent in the course of the following description of one embodiment of the invention, taken in connection 45 with the accompanying drawings wherein

Fig. 1 is a front elevation of a locker in which is embodied the novel features of the present invention;

Fig. 2 is a fragmentary view, taken on the

line 2—2 of Fig. 1, and showing the slots in the tubular reinforcement and latching bar for the reception of the bolt of a key-lock;

Fig. 3 is a cross-section through the tubular reinforcement and the latching bar, taken on the line 3—3 of Fig. 1;

Fig. 4 is a cross-section through the door and adjacent portions of the locker, taken on the line 4—4 of Fig. 1;

Fig. 5 is a cross-section through the tubular reinforcement and adjacent portions of the locker, taken on the line 5—5 of Fig. 1;

Fig. 6 is a cross-section, taken on the line 6—6 of Fig. 1, and showing the manner in which the handle is secured to the latching 65 bar;

Fig. 7 is an exploded view of the handle, a portion of the tubular reinforcement, and a portion of the latching bar, showing the relation of these parts before assembly; 70

Fig. 8 is a fragmentary perspective view of the upper end of the tubular reinforcement and the latching bar, showing the manner in which the latching bar is retained in position by the reinforcement; 75

Fig. 9 is a perspective view of the latching bar, and

Fig. 10 is a cross-section through the latching bar, taken on the line 10—10 of Fig. 9.

Referring more particularly to the drawings, the locker includes a sheet-metal door frame 1, and a door 2 hinged thereon. The door 2 is formed at one of its side edges with a tubular reinforcement consisting of two spaced box-flanges 3 and 4, each of which includes inner legs 5 and outer legs 6, and an intervening connecting web 7, which may be spot welded or otherwise secured to the rear face of the door. The upper and lower ends of connecting web 7, and portions of the legs 80

5 of the box-flanges are cut away to provide stops 8 and 9, as clearly shown in Fig. 3, and for another purpose which will become apparent later. The leg 6 of the box-flange 3 85 may also be spot welded or otherwise secured to the rear face of the door, as clearly shown in Fig. 4. The tubular reinforcement is closed at the top and bottom by means of door flanges 10 and 11, provided with T-slots 95

12, which serve a purpose to be presently de- 100

scribed. Intermediate its ends, the web 7 is provided with spaced slots 13, these slots also extending through the door proper.

The latching mechanism includes a channel bar 14, the flanges 15 and 16 of which are formed at their extremities with laterally projecting wings 17, and intermediate their ends, with spaced inturned retaining lugs 18, which substantially abut each other, as shown in Fig. 10. The flanges of the channel bar are also provided with spaced extrusions 19, which facilitate vertical sliding movement of the bar when in position on the door, and the leg 15 of the bar is further provided with a slot 20, which serves to receive the bolt of a key-lock 21, shown in Fig. 1. The web 22 of the channel bar is provided at spaced intervals with slots 23, terminating in upper edges 24 and lower edges 25.

20 The latching mechanism also includes hooks or keepers 26, mounted on the door frame 1. Each of these keepers is formed with an upwardly sloping edge 27, a downwardly sloping edge 28, approximately twice 25 as long as the edge 27, and a seat 29.

A handle 30 is provided, consisting of a flat strip 31, suitably mortised to receive the tenons 32 of a U-shaped gripping member 33. After the tenons are inserted through the mortises in the flat strip 31, they are bent upward to provide stops 34, as clearly shown in Figs. 1 and 5. Prior to assembling the various parts of the latching mechanism, a headed screw 35 is inserted into, but not 35 through, the lower stop 34.

The various parts of the latching mechanism are assembled as follows:

The wings 17 at the upper end of the latching bar are first caused to enter the T-slot 40 12 in the flange 10, and the bar permitted to drop down until the lower ends of the wings abut the stop 8. The opposite end of the bar is then inserted in like manner through the T-slot 12 in the flange 11. The bar is then 45 moved upwardly to its upper limit of movement, and at this point, the lugs 18 will occupy a position just above the slots 13. The tenons 33 of the handle are then inserted through the slots 13, and moved inwardly until the stops 34 occupy the position shown 50 in Fig. 3. The latching bar is then permitted to drop down to the position shown in Fig. 3, whereupon the lugs 18 secure the handle against retraction. In order to limit the 55 degree of relative movement between the latching bar and the handle, the screw 35 is screwed inwardly, as by means of a screw driver inserted through an opening 36 in web of the bar, until its inner end overlies the lower lugs 18, as shown in Figs. 3 and 6.

From the foregoing description, it will be readily understood that the various parts of the latching mechanism and the handle may be readily disassembled, when it is desired to repair or replace a defective or worn

out part, by a simple reversal of the operations.

It will also be apparent from a consideration of Figs. 3 and 4, that when the door is closed, the upper edges 24 of the slots 23 in 50 the latching bar will ride up over the upwardly sloping edges 27 of the keepers 26, until the uppermost point of these edges is reached. The lower edges 25 of the slots 23 will then begin to contact with the downwardly sloping edges 28 of the keepers, and the edges 24 of the slots will be positively forced to move down into the seats 29. In 55 manner, the locker door is effectively shut or latched, regardless of how slight or great 80 a force is employed to effect the latching.

Claims:

1. In a locker door, a reinforcement extending along one edge of the door and comprising spaced flanges, and a latching bar mounted for vertical movement between the flanges and provided with means for engaging the flanges to prevent detachment of the bar from the door.

2. In a locker door, a reinforcement extending along one edge of the door and comprising spaced flanges, portions of said flanges being cut away to provide stops, and a latching bar mounted for vertical movement between the flanges and provided with 90 means for abutting the stops to limit the vertical movement of the bar.

3. In a locker door, the combination of a latching bar provided intermediate its ends with inturned retaining lugs, and a handle provided with tenons adapted for interlocking engagement with said lugs.

4. A structure as defined in claim 3, in which the latching bar is of channel cross-section, and the lugs are formed by striking 105 inwardly, portions of the flanges of the bar.

5. A structure as defined in claim 3, and means for limiting the degree of relative movement between the handle and the latching bar.

6. In a locker door, a reinforcement extending along one edge of the door and comprising spaced flanges, and a latching bar movably secured to said flanges and restrained from lateral movement thereby.

In testimony whereof I affix my signature.

SHIRLEY S. FRENCH.
